UNITED STATES PATENT OFFICE

FRANK C. BURTON, OF CHICAGO, ILLINOIS

DESIGN FOR A RADIOCABINET

Application filed August 12, 1929. Serial No. 32,387. Term of patent 3½ years.

To all whom it may concern:

Be it known that I, FRANK C. BURTON, a citizen of the United States, residing at Chicago, Illinois, post-office address 64 East Lake Street, Chicago, Illinois, have invented a new, original, and ornamental Design for a Radiocabinet, of which the following is a specification, reference being had to the accompanying drawings, forming part thereof.

In the drawings:

Fig. 1 is a perspective view showing the front and one side of the cabinet with the front doors closed; and

Fig. 2 is a similar view with the front doors open.

I claim:

The ornamental design for a radiocabinet as shown.

FRANK C. BURTON.
